(57) **CLAIM**

The ornamental design for a sound machine for sleep therapy, as shown and described.

DESCRIPTION

FIG. 1 is a front perspective view of a sound machine for sleep therapy according to an embodiment of the invention shown;

FIG. 2 is a rear perspective view of the sound machine for sleep therapy of FIG. 1;

FIG. 3 is a front perspective view of the sound machine for sleep therapy of FIG. 1;

FIG. 4 is a rear perspective view of the sound machine for sleep therapy of FIG. 1;

FIG. 5 is a right side elevation view of the sound machine for sleep therapy of FIG. 1;

FIG. 6 is a left side elevation view of the sound machine for sleep therapy of FIG. 1;

FIG. 7 is a top plan view of the sound machine for sleep therapy of FIG. 1;

FIG. 8 is a bottom plan view of the sound machine for sleep therapy of FIG. 1;

FIG. 9 is a front elevation view of the sound machine for sleep therapy of FIG. 1; and,

FIG. 10 is a rear elevation view of the sound machine for sleep therapy of FIG. 1.

In FIG. 1, the broken lines are for the purpose of illustrating environment only and form no part of the claimed design.

1 Claim, 8 Drawing Sheets
